UNITED STATES PATENT OFFICE.

JENNIE J. FREDERICKSON, OF SPRINGFIELD, MINNESOTA.

COIN AND PEN HOLDER.

1,218,843.

Specification of Letters Patent. Patented Mar. 13, 1917.

Application filed October 20, 1916. Serial No. 123,756.

To all whom it may concern:

Be it known that I, JENNIE J. FREDERICKSON, a citizen of the United States, residing at Springfield, in the county of Brown and State of Minnesota, have invented certain new and useful Improvements in Coin and Pen Holders, of which the following is a specification.

The present invention relates to article 10 holders and has particular reference to new and useful improvements in coin and pencil holding devices, the device having as its primary object the provision of a coin and pencil holder which is readily adaptable 15 for application to a book or the like to receive pencils, pens, coins and the like and retain the same against loss.

Another object of my invention is to provide a device of the character referred to 20 which is simple in construction, strong and durable, effective in operation and cheap to manufacture.

A further object of my invention is to provide a coin and pencil holder of the class 25 described combined in a novel manner for retaining pencils, pens, coins and the like articles to prevent loss of the same, the holding devices being arranged within a suitable receptacle, which latter is adapted to be 30 attached to a book or the like ordinarily carried by students and others in order that the device will not consume more space than is necessary.

Other objects and advantages to be derived from the use of my improved coin 35 and pen holder will appear from the following detailed description and the claims, taken with an inspection of the accompanying drawing, in which:

40 Figure 1 is a perspective view of a coin and pencil holder embodying the improvements of my invention; and

Fig. 2 is a transverse sectional view of the same on line 2—2 of Fig. 1 with the pen 45 and pencil removed.

Referring more particularly to the drawing, wherein similar characters of reference designate like and corresponding parts throughout the various views, A designates 50 in its entirety the container for the holding device, said container having a bottom 1 and side and end walls 2 and 3, respectively. The receptacle A is provided with a lid 4 hingedly connected at 5 to one of the side

walls 2. A spring catch 6 is carried by the 55 lid for an obvious purposes.

A clamp for attaching the receptacle A to an object is provided composed of the sections c and c', said sections being U-shaped in cross section and arranged in telescopic relation. The section c is formed with flanges 7 and 8 to receive the spaced portion 9 of the section c'. The bottom 1 of the receptacle A is connected with the section c by means of rivets 10 or the like. 60

The pencil and coin retaining element of my invention is preferably formed of a single strand of wire provided with a coiled portion 11 arranged transverse of the receptacle A, the free end 12 of the coil 11 lying 70 upon the bottom of the container and coiled as at 13 to provide coin holders. The convolutions of the pencil holding coil 11 are preferably rectangular in cross section so as to more firmly retain the objects inserted 75 thereinto.

In use pencils, pens and the like are to be inserted between the convolutions of the spring 11, said pencils and the like being retained therein by virtue of the resiliency 80 of the spring. The portion 12 of the strand of wire from which the springs 11 and 13 are formed are attached to the base or side walls of the receptacle by soldering or the like. 85

It is preferable that the clamp be applied to the back of a book, said book being designated b and shown in Fig. 1. Coins are inserted beneath the spring 13 as best shown in Fig. 1, said spring serving to prevent 90 displacement of the coin and yet permitting ready removal of the same. Thus it will be seen that in the provision of my improved pencil, pen and coin holder I have afforded a compact and effective device for carrying 95 objects which may be associated with the usual student's outfit without inconvenience. The inner surface of the top is nickelized or the like to form a mirror.

From the above description taken in connection with the accompanying drawing, it is thought that a clear and comprehensive understanding of the construction, operation and advantages of my invention may be had, and while I have shown and described the 105 device as embodying a specific structure, I desire that it be understood that such changes may be made in said structure as

do not depart from the spirit and scope of the invention as claimed.

Having thus fully described my invention, what I claim as new and desire to secure by Letters Patent, is:—

1. In a device of the character described, the combination of a container, means to connect said container with a supporting object, an object retaining device arranged within the container, said retaining device comprising a main coil spring portion, formed from a strand of wire having the free ends thereof secured to the container, said free ends being provided with coils ar-

ranged adjacent one end of the container 15 remote from said main coil, and a closure for the container.

2. In a device as specified, the combination with a housing, of an object retaining member therein formed of a strand of wire provided with a main coiled portion arranged transversely of the housing, the free ends of the strands being provided with coils 20 to retain objects.

In testimony whereof, I affix my signature 25 hereto.

JENNIE J. FREDERICKSON.
